DESIGN.

J. L. FOLSON.

CARPET.

No. 18,228.

Patented Apr. 3, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,228, dated April 3, 1888.

Application filed January 26, 1888. Serial No. 262,045. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of the irregularly-shaped figures A, B, C, and D disposed over the surface of the carpet, substantially as shown.

Figure A is a composite figure having an 20 irregular indented outline. Its central portion is ornamented with coral-like forms. Around the central portion is a band of varying width and uneven outline, ornamented with small geometrical forms or cellular-like work. Out- 25 side of this band is a less prominent border or margin, in places assuming the form of a leaf.

Figure B is a composite figure having an ir-

regular indented outline. The central portion is ornamented with coral-like forms. Surrounding this portion is a band or border of varying width ornamented in part with cellular-like work and in part with leaf forms.

Figure C is a composite figure having an irregular indented outline. The central portion is ornamented with coral-like forms. Around the central portion is a band or border of varying width, consisting in part of a single or double row of cellular-like forms and in part of leaf forms.

Figure D is a composite figure of a general 40 triangular shape, having an irregular indented outline. Its central portion is ornamented with coral-like forms. Around this central portion is a band or border of varying width, consisting of cellular-like work and leaf forms. 45

What I claim as new, and desire to secure by Letters Patent, is—

The design for carpets, consisting of the design substantially as shown.

JAS. L. FOLSOM.
